UNITED STATES PATENT OFFICE.

JOSEPH HENRY NUTON GUILFORD, OF WHIGHAM, GEORGIA.

FISH-PLATE-FASTENING MACHINE.

SPECIFICATION forming part of Letters Patent No. 313,418, dated March 3, 1885.

Application filed January 7, 1884. (Modcl.)

To all whom it may concern.

Be it known that I, JOSEPH HENRY NUTON GUILFORD, of Whigham, in the county of De- 5 catur and State of Georgia, have invented a new and Improved Fish-Plate-Fastening Machine, of which the following is a full, clear, and exact description.

My invention relates to improvements in fish-joint-fastening machines; and it consists 10 in the peculiar construction and arrangement of parts, as hereinafter fully described, and pointed out in the claims.

Reference is to be had to the accompanying drawings, forming part of this specification, in 15 which similar letters of reference indicate corresponding parts in all the figures.

Figure 1 is a sectional elevation of my improved machine, and of a fish-joint to which the machine is applied for screwing up the 20 nuts, on line $x^2 x^2$ of Fig. 2. Fig. 2 is a plan view of the machine with a detail in section. Fig. 3 is a section on the line $y y$, Figs. 1 and 2. Fig. 4 is an end elevation. Fig. 5 is a detail of the wrench-adjusting devices. 25 Fig. 6 is a section of one of the wrenches, showing the application of a screw-cutting die to run over the screw-threads of the bolts when required. Fig. 7 is an end elevation of Fig. 6. Fig. 8 is a section of one of the wrenches, 30 showing the application of a reamer to bore or ream out and enlarge the holes of the fish-plate when required. Fig. 9 is an end elevation of Fig. 8. Fig. 10 is a plan view of a feeding-clamp to be employed with the drill or 35 reamers when used for boring the rails and enlarging the bolt-holes in the fish-plates; and Fig. 11 is a section of the feeding-clamp and the fish-joint.

I mount a couple of socket-wrenches, a , on 40 spindles b , arranged side by side horizontally in a bed-frame consisting of cross-bars c and side bars, d , and having the side bars, d , fitted at one end, e , to the shape of the side of a rail, f , and provided with a clamp to clamp the 45 frame fast to the side of the rail, said clamp consisting of the fulcrum-stirrup links g , yoke-lever h , bearing-bar i , and the holding-pawl j . The fulcrum-links g are pivoted to the side bars, d , of the frame at k , and extend over 50 across the rail f to the yoke-lever h , to which they are pivoted at l . The bearing-bar i is attached to the lower ends of the arms of the

yoke-lever to bear against the fish-plate m , and the pawl-bar j is pivoted at n to the upper end of one of a pair of housing-frames, O , and 55 has a notched portion, p , extending through a slot, q , of the upper end of the yoke-lever, in which it is secured, when adjusted, by a key, s , to bind the clamp fast on the rail. The bearing-bar i also has sockets t , that fit on the heads 60 of the fish-joint bolts u , to prevent them from turning when the nuts v are being screwed on. The sockets t are located in the bearing-bar i , so that they will receive and hold the heads of the two bolts on one side of the rail-joint 65 while the socket-wrenches a are screwing on the nuts, the spindles of the wrenches being also arranged the same distance apart as the the bolts are placed from each other in the fish-joint, and they are coincident with the 70 sockets t to apply the nuts when the bolts are held in said sockets. The wrench-spindles b are fitted in bearings w of the cross-bars c , so that they may be pulled back by a handle, x , and cross-bar y , to place the nuts v in the 75 sockets z of the wrenches, and the spindles have springs a' to press them forward to enter the nuts on the ends of the joint-bolts. The cross-bar y pulls against the stud-pins b' to slide the spindles back, and the springs a' 80 bear against the same studs to push the spindles forward, said springs being supported at the other end against the cross-bar c of the frame.

To hold the spindles back against the springs 85 while adjusting the nuts, and for any other purpose, the bar c' , connecting handle x with cross-bar y , has a notch, d' , and a latch, e' , is fitted on the cross-bar c to drop into the notch, said notch being so located on the bar c' that 90 it comes out to and receives the latch when the wrenches are pulled back. The wrenches a are fitted on the spindles by sockets f' , square shanks g' of the spindles, and set-screws h' , to enable them to be taken off quickly in case it 95 may be desired to remove a nut that is too slack and put on another, or for any purpose. To apply power to the spindles for turning the wrenches, said spindles are each fitted with a long pinion, i' , with both of which an intermediate wheel, j' , gears, to which power is applied by a driver, k' , on the crank-shaft l' . The crank-shaft l' and the shaft m' of the intermediate wheel are mounted in the hous-

ings o , suitably for gearing with the wrench-spindles, so that the crank n' will swing clear of the ground and the handle x .

To apply additional power to the driving-wheel k' when the nuts turn very hard, the said driving-wheel is provided with staples o' at intervals around it on one side, in which a hand-lever, p' , may be inserted for a purpose to screw the nuts home with a powerful thrust.

It may sometimes be preferred to use the smaller wheel j' for the driver and the larger wheel k' for the intermediate, and I have prepared bearings q' in the housings for shaft l' , and bearings s' for the shaft m' , enabling the shafts to be shifted readily. In such case the two shafts will be fitted alike for the crank n' , so that it may be very readily changed from one to the other.

This machine can be readily clamped to either side of the rail, so as to be suitably supported for connecting the wrenches with the nuts, with the back end of the frame resting on the ties or on the ground, and it affords a simple and convenient means of screwing up the nuts more rapidly and powerfully than can be done by hand. It is first applied to the nuts of one end of the rail-joint, and is then shifted along to the next. If preferred, one of the wrenches may be taken off and the other one used alone. Sometimes bolts u will be formed on which the threads have not been sufficiently cut, in which case I have a socket-screw cutting-die, u' , to fit in the socket z of the wrenches, and be secured by a set-screw, v' , to be run on the bolts, the same as the nuts are run, to properly reduce and finish the threads; but in this case the die u' will be withdrawn by turning the crank backward.

The die u' may be made in two parts with connecting-screws w' , by which the parts may be set as required for the size of the bolts.

For reaming out the holes of the fish-plates when it may happen that they are too small for the bolts, and also for boring out holes in the rails when necessary to fit holes corresponding to holes in the fish-plates, I provide a socket, c^2 , to fit the sockets z of the wrenches,

with a reamer, d^2 , to be carried therein for turning the reamer by the hand-power apparatus, as indicated in Figs. 10 and 11, and also provide a clamp to force the reamer into the holes, consisting of the clamp-plate e^2 , having flanges f^2 , bearing against the ends of the socket-wrenches a , and also having the flange g^2 , turning down the side of the rail, and carrying a feed-screw, h^2 , by which to force the reamers in. The flanges f^2 of the clamp-plate e^2 are notched suitable for straddling the wrench-shafts to bear against the wrenches on each side of the shafts.

The improved machine will effect considerable saving of time and labor in the fastening of fish-plates, besides enabling the joints to be fastened more effectually.

Having thus described my invention, what I claim as new, and desire to secure by Letters Patent, is—

1. In a fish-plate-fastening machine, the combination, with a frame carrying wrenches, of a clamping device consisting of the links g , yoke-lever h , bearing-bar i , and holding-pawl j , substantially as herein shown and described.

2. In a fish-plate-fastening machine, the combination, with the frame consisting of the bars c and uprights O , of the shafts l' m' , the gears $i' j' k'$, the spindles $b b$, the wrench-sockets $a a$, and the springs a' , substantially as herein shown and described.

3. In a fish-plate-fastening machine, the combination, with a supporting frame and the sliding spindles b , provided with wrenches a on their ends, of the long gear-wheels i' , mounted on said spindles, and the gear-wheels $j' k'$, substantially as herein shown and described.

4. In a fish-plate-fastening machine, the combination, with the spindles $b b$, having wrench-sockets $a a$ and pins b' , of the bar c' , having handle x and cross-bar y , and provided with the notch d' , the springs a' , and the latch e , substantially as herein shown and described.

JOSEPH HENRY NUTON GUILFORD.
